UNITED STATES PATENT OFFICE.

RUDOLPH WOLF, OF BRIDGEPORT, CONNECTICUT.

GRINDING-MACHINE.

SPECIFICATION forming part of Letters Patent No. 752,500, dated February 16, 1904.

Application filed November 13, 1903. Serial No. 181,018. (No model.)

To all whom it may concern:

Be it known that I, RUDOLPH WOLF, a citizen of the United States, residing at Bridgeport, county of Fairfield, State of Connecticut, have 5 invented a new and useful Grinding-Machine, of which the following is a specification:

My invention relates to grinding-machines more especially adapted for grinding knife-blades, and has for its object to produce a 10 machine of this character which shall be inexpensive to make, easy to operate, and rapid in operation, and which will grind the blades either "flat" or "rounded," so called—that is, slightly convex—or if a relatively small stone 15 is used will grind the blades concave.

With the above ends in view I have devised the novel grinding-machine which I will now describe, referring to the accompanying drawings, forming a part of this specification, and 20 using reference characters to indicate the several parts.

Figure 1 is a plan view of my novel machine complete, showing the position of the parts at the instant of finishing the grinding of a blade; 25 Fig. 2, a section on the line 2—2 in Fig. 1; and Fig. 3 is an enlarged elevation of the blade-carrying block detached, showing a blade in position thereon.

10 denotes framework of any ordinary or 30 preferred construction, and 11 a table sliding in ways 13 in the framework. Upon the under side of the table is a rack 14, which is engaged by a pinion 15 on a transverse shaft 16, shown as journaled in hangers under the 35 table. At one end of the shaft is a crank 17, connected by means of a rod 18 to a foot-lever 19. At the opposite end of the crank is an arm 20, which carries an adjustable counter-weight 21.

40 22 indicates a grinding-wheel. The action of the counterweight is to oscillate the shaft and by means of the rack and pinion move the table forward and retain it in operative position, as will be more fully explained. To 45 move the table backward away from the grinding-wheel in order to remove a ground blade and place another in position to be operated upon, the operator simply presses down upon

the foot-lever. Any other convenient means for moving the table backward may of course 50 be substituted, if preferred.

23 indicates a blade, which is shown as carried by a block 24. This block in practice is ordinarily made of maple wood, although the material of which the block is made is unim- 55 portant so far as the principle of the invention is concerned. This block rests in a U-shaped holder 25, which is pivoted to oscillate in the vertical plane in an opening 26 in a carrier 27, which itself oscillates in the horizontal 60 plane, being pivoted on a central stud 28, which engages the table. The U-shaped holder is shown as swinging on screw-studs 29, which engage the carrier, and as provided with a hand-piece 30 for convenience in operation. 65 The block is shown as adjustably secured to the holder by means of bolts 31, which pass through slots 32 in the block.

33 denotes an arm rigidly secured to the carrier and extending forward over the rear 70 end of the block and provided at its forward end with a set-screw 34, engaging the block, which determines the adjustment of the surface to be operated upon relative to the grinding-surface and retains the block and the 75 blade carried thereby in position for flat grinding.

35 denotes hand-levers pivoted on opposite sides of the table, as at 36, whose forward ends bear against the rear end of the carrier, forming a convenient means for oscillating the carrier in the horizontal plane, as is required in grinding a blade from end to end, ordinarily from heel to point. The blade may be retained in position on the block in any convenient 80 manner, as by a lug or pin 37, against which the back of the blade rests, and a hook 38, shown as engaging the usual shoulder in the butt of a jackknife-blade. The carrier is normally retained in a central position in any convenient manner, as by coil-springs 39, the inner ends of which are connected to the carrier and the outer ends to opposite sides of the table, as at 40.

In use the operator places the machine and 95 the grinding-wheel in such a position relative

to each other that one side only of the face of the wheel will be operative and while the machine and the wheel are in this position grinds one side of any required number of blades, 5 after which either the machine or the grinding-wheel is shifted so that the other side of the face of the wheel will be in operative position. Then the opposite side of the blades is ground. In Fig. 1 the carrier is shown in its normal 10 position, as when the grinding of a blade has been finished. With the parts in this position the operator would, by means of the foot-lever, move the carrier backward, remove the blade therefrom, and place another blade in 15 position to be operated upon. As soon as the pressure upon the foot-lever is relieved the counterweight 21 will return the carrier to its normal position and place the blade in contact with the grinding-wheel. The operator, 20 by means of one of the hand-levers 35—in the present instance the hand-lever toward the bottom of the sheet—oscillates the carrier on its pivot until the blade is placed in such a position that the heel of the cutting edge will 25 come in contact with the grinding-wheel, it being of course understood that the counterweight will retain the blade in contact with the wheel no matter what may be the position of the carrier. During the grinding operation 30 the operator, by means of either or both of the hand-levers 35, oscillates the carrier and causes the blade thereon to pass longitudinally over the face of the wheel, the grinding of each blade being finished at the 35 tip, as indicated in Fig. 1. This operation with a grinding-wheel of what may be termed “ordinary” size produces what is termed a “flat” grind. To produce a concave grind by the same operation, it is simply required to 40 use a smaller grinding-wheel. The position in which the side of the blade—*i. e.*, the surface to be ground—is presented to the grinding-wheel is determined by the adjustment of the set-screw in arm 33. By turning this set-screw inward the rear end of the block will 45 be depressed and the front end correspondingly raised, thereby raising the blade relative to the grinding-wheel and changing the line of action of the grinding-wheel thereon. 50 When it is desired to impart a slightly convex form to the blades—that is, produce what is called a “rounded” grind—set-screw 34 is turned outward far enough so that it will not be engaged by the rear end of the block and 55 the block, with the blade thereon, is oscillated in the vertical plane—*i. e.*, swung upward and downward at the same time that it is being passed longitudinally across the face of the grinding-wheel by movement of the carrier— 60 handpiece 30 being provided for convenience in oscillating the block. This handpiece may be used upon either side, as convenient, or may be removed from the machine when it is not desired to round the blades.

Having thus described my invention, I 65 claim—

1. In a grinding-machine the combination with a blade-carrying block and an oscillatory carrier therefor, of means for oscillating said carrier in the horizontal plane. 70

2. In a grinding-machine the combination with a blade-carrying block and a carrier therefor pivoted to swing in the horizontal plane, of means as a hand-lever bearing against the carrier whereby a blade may be passed 75 from end to end over the face of a grinding-wheel, and springs for returning the carrier to its normal position when the action of the lever is relieved.

3. In a grinding-machine the combination 80 with a reciprocating table provided with a rack, a pinion and connections for moving the table backward and a counterweight acting to retain the table in operative position, of a carrier pivoted to the table and adapted to oscillate in the horizontal plane and a knife-carrying block adjustably secured to the carrier. 85

4. In a grinding-machine the combination with a reciprocating table provided with a rack, a pinion engaging the rack, a shaft by 90 which the pinion is carried and which is provided with a crank and an arm, crank connections by which the table is moved backward and a counterweight on the arm for retaining the table in operative position, of an 95 oscillating carrier pivoted to the table and a knife-carrying block adjustably secured to the carrier.

5. In a grinding-machine the combination with a knife-carrying block and a U-shaped 100 holder to which the block is adjustably secured, of a carrier pivoted to oscillate in the horizontal plane, and having an opening in which the holder is pivoted to oscillate in the vertical plane, and a set-screw for determining 105 the position in which the surface to be ground is presented.

6. In a grinding-machine the combination with a reciprocating table and a horizontally-oscillating carrier pivoted thereto and provided with an opening, of a vertically-oscillatory U-shaped holder pivoted in said opening, a slotted blade-carrying block and bolts 110 engaging the holder whereby the block is adjustably secured thereto. 115

7. In a grinding-machine the combination with a horizontally-oscillating carrier and a vertically-oscillating blade-carrying block pivoted thereto, of means as a set-screw for adjusting the plane of the block so as to vary 120 the position of a blade on the block relative to a grinding-machine.

8. In a grinding-machine the combination with a blade-carrying block and a holder therefor, of a horizontally-oscillating carrier to which the holder is pivoted to oscillate in the vertical plane, and a set-screw engaging the block whereby the position of a blade carried 125

thereby relative to a grinding-wheel may be regulated.

9. In a grinding-machine the combination with a blade-carrying block and a holder therefor, of a horizontally-oscillating carrier to which the holder is pivoted to oscillate in the vertical plane so that oscillation of the carrier will move the blade longitudinally across the face of a grinding-wheel and oscillation of the

holder will oscillate the blade in the plane of rotation of the wheel and produce a round-ing grind.

In testimony whereof I affix my signature in presence of two witnesses.

RUDOLPH WOLF.
